DESIGN FOR A HOLDER FOR THREAD SPOOLS OR SIMILAR ARTICLES

Jennie Edelstein, Miami Beach, Fla.

Application April 17, 1939, Serial No. 84,354

Term of patent 7 years

To all whom it may concern:

Be it known that I, Jennie Edelstein, a citizen of the United States, residing at Miami Beach, in the county of Dade and State of Florida, have invented a new, original, and ornamental Design for a Holder for Thread Spools or Similar Articles, of which the following is a specification, reference being had to the accompanying drawing, forming part thereof.

The single figure is a perspective view of a holder for thread spools or similar articles, showing my new design.

The opposite side is substantially the same as that shown.

I claim:

The ornamental design for a holder for thread spools or similar articles, as shown and described.

JENNIE EDELSTEIN.
